UNITED STATES PATENT OFFICE.

EDMUND M. ERB, OF HARTFORD, CONNECTICUT, ASSIGNOR TO KEEN WAVING COMPANY, INCORPORATED, OF NEW YORK, N. Y., A CORPORATION OF NEW YORK.

POWER CHANDELIER.

Application filed May 20, 1927. Serial No. 193,049.

The invention relates in general to an overhead bracket or chandelier for supplying electric current to a plurality of suspended electric instruments and the invention specifically relates to a chandelier used in the art of permanent hair waving for supplying electric energy to a plurality of heaters positioned on the head of the person under treatment.

10 The primary object of the invention is to provide a simple form of chandelier which will be neat in appearance, which will provide a support for a maximum number of heaters within a limited space and which 15 will provide for a grouping of these heaters in close position encircling the head of the person under treatment. The invention further features the providing of suspending means for the electric leads supplying 20 the heaters and which means will cause the leads to group themselves so as to minimize tendency of intertwining or entangling.

Chandeliers of the type under discussion are frequently used by hair dressers and 25 others not particularly skilled in their mechanical ability to make small repairs and it would be commercially impracticable and otherwise too difficult to return a damaged chandelier to a factory or service station for 30 all minor repairs.

Accordingly, another object of the invention is to provide a form of chandelier in which parts most likely to be damaged or worn in use can be readily separated from the device and replaced with repair or substitute parts or in which such damaged or worn parts may even be removed and discarded without impairing the operativeness of the balance of the device.

40 Another object of the invention in such a device which is characterized by the ready removability of certain parts is to provide for the demounting of such parts either without the use of any tools whatsoever or with 45 a screw driver or other tool commonly found in households.

Accordingly, the invention features the standardizing of the parts of such a machine which are most likely to need repairing. 50 Specifically, the elevators which control the raising of those heaters which are not in use into an out-of-the-way position and the asso-

ciated electric leads are the parts which are most likely to need repairs and replacements. Accordingly, the invention features providing of elevators designed so that they may be readily withdrawn from the device simply by unhooking them from their supports and in which the electric leads associated with such demounted elevator may be easily demounted and quickly restored into operative position engaging a replaced or repaired elevator.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawing:

Fig. 1 is a view with the right half in side elevation and partly broken away, and the left half partially in axial section through a preferred embodiment of the invention and showing a pair of heater cables supplied from one of the sockets and with the elevator associated with one of the cables shown in full line and in lowered position and the elevator controlling the other cable shown in dotted lines and elevated;

Fig. 2 is a segmental section of a part of the device shown in Fig. 1 with the enclosing dome omitted to show the construction therein;

Fig. 3 is a view in side elevation of one of the elevators constituting an enlargement of the elevator shown to the left of Fig. 1;

Fig. 4 is a sectional view taken on the line 4—4 of Fig. 3;

Fig. 5 is a view in side elevation of an elevator illustrating a modified form of pivotal mounting;

Fig. 6 is a detail of the guiding ring shown in vertical cross section as taken on the line 6—6 of Fig. 2;

Fig. 7 is a view similar to Fig. 1 showing a modified form of the invention; and

Fig. 8 is a view similar to Fig. 2 of the form shown in Fig. 7.

In the drawings and referring first to Fig.

1, there is shown a depending support 10 in the form of a hollowing post adapted to be carried by an arm 11 in turn supported for vertically adjustable movement and containing 5 an electric power cable 12. Secured to the flange 13 forming the lower part of the post 10 and depending therefrom is a central support 14, the upper portion of which is a spool-shaped cylindrical member 15 and the lower portion of which is a frusto-conical shell 16. The spool-shaped member 15 includes an upper flange 17 to which is secured the upper inner edge of a mechanism containing dome 18 fastened in place by means of screws 19. 10 The lower flange 20 of the member 15 provides a seat for an elevator stop plate 21, the outer circular edge 22 of which is adapted to limit the upward movement of elevators 23 hereinafter described and as shown in 15 dotted lines in Fig. 1. Extending across the lower open end of the cone shell 16 is a spider 24 and the bottom of the dome 18 is closed by means of a bottom cover plate 25 secured centrally to the spider 24. 20 Secured to the underside of the cone 16 by means of the screws 26 and which screws also secure the spider in place, is a box 27 including an outlining peripheral wall 28 which forms a mounting for a series of double plug 25 sockets 29 extending therethrough. The lower edge of the wall 28 is outbent as shown at 30 and is secured to the cover plate by means of the screws 26. The portion of the cover plate 25 exteriorly of the box 27 constitutes or is provided with means for guiding 35 the cables 31 leading to electric heaters 32. This outer portion of the bottom cover plate is referred to hereinafter as a guide mounting plate 33. 40 The guide mounting plate is provided with a plurality of passageways 34 (see Fig. 2), one for each of the sockets 29 and the center of each passageway is disposed approximately in axial alignment with the associated socket. 45 Each passageway 34 is provided with a pair of diametrically disposed slots 35 and 36, (see Fig. 2) disposed on opposite sides of the axis of its associated socket and each provided with a guiding ring 37 (see Fig. 5) inserted in place through the associated passageway and moved edgewise to the end of the slot where it is held in position by a U-shaped spring clip 38 fitted between an end flange 39 and the adjacent face of the plate. 50 A flange 40 defining the opposite end of the ring bears on the opposite or underside of the plate 33 as particularly shown in Fig. 5. From this construction, it is apparent that one or both of the guiding rings can be readily 55 demounted simply by withdrawing its holding clip and sliding the same out through the passageway. 60 In manufacturing the replaceable unit including the electric leads, the guiding rings 65 will be mounted one on each of the cables 31

and positioned between the heater 32 at one end of the cable and the screw plug 41 at the other end of the cable and which plug when screwed into position constitutes the removable element of the socket 29. In the showing illustrated two cables and therefore two electric heaters are connected to each plug 41 as shown in the upper part of Fig. 2. Differently expressed, a single socket supplies two adjacent electric heaters but it is obviously within the scope of the disclosure to supply more than two heaters from a single socket. In this case, it will be necessary to provide additional slots radiating from the passageway 34 so as to guide the cables so as to fall free of each other. The several sockets are supplied from the power lead 12 by branch conductors 42 leading circularly about the inside of the box 27 to the several sockets in the completed circle of sockets. 70 75 80 85 90 95 100 105 110 115 120 125 130

It is desirable in devices of the class described to elevate the heaters when not in use into an out-of-the-way position and for this purpose there is disclosed cable elevators 23 which are pivoted at their inner ends to the central cone 16 and having a length so that when raised they take up the slack in the cables. These elevators have each rotatably mounted at its outer end a pulley 43 about which are turned cable 31, one cable to each elevator as particularly illustrated in Fig. 2. The elevators are each controlled by an upwardly extending spring 44 acting on the elevators when released from the weight of the heaters to move into the elevated position shown in dotted lines in Fig. 1 and in position to raise its associated heater from its operative position adjacent the person's head into the raised position as shown to the left of Fig. 1. The elevators are limited in their upward movement by abutting against the outer edge 22 of the stop plate and are limited in their depressed position by engagement with the mounting plate 33. 105

It is a feature of this disclosure that the elevators be designed so as to be quickly removed. For this purpose, the inner pivotally mounted ends of the elevators are provided in the form shown in Figs. 3 and 4 with an upwardly facing slot 45 designed to receive and overlap a pivot pin 46 and which preferably is a wire as shown in Fig. 2 threaded through fingers 47 forming extensions from the lower part of the cone 16. Similarly the upper ends of the springs 44 engage a wire 48 threaded through fingers 49 constituting projections from the upper side of the cone 14. From this construction it is appreciated that the springs may be readily demounted from the wire 48 as by unhooking the same and the elevators may be removed from their pivotal connections simply by withdrawing the lower ends of the elevators from the wire 48 when the elevator is in the upwardly disposed position shown in dotted lines in Fig. 1. With 110 115 120 125 130

the elevator separated from the cone, it may be withdrawn through the passageway 34, which is of sufficient cross sectional area to permit the removal of the elevator as a whole.

5 It is also understood that the plug 41 may be similarly withdrawn through the passageway 34 in demounting the cable 31 and plug as a whole from its associated socket.

The specific form of elevators selected 10 herein for illustration in Figs. 3 and 4 includes a readily demountable form of pulley and means for securing the cable in engagement with the pulley so that it will not accidentally slip off the pulley. In the showing 15 in Fig. 4, it will be noted that the elevator is formed of a pair of parallel side plates 50 connected by a pair of spacing rivets 51. The plates at one end are offset from each other to provide a broad bearing 52 containing the 20 slots 45 and the opposite end mounted so as to be sprung apart. This opposite end is provided with oppositely disposed integral aligned pivot studs 53 which coact to provide a pivotal bearing for the pulley 43. The 25 pulley containing ends of the plates 50 are held in position to mount the pulley rotatably by means of a clamp 54 straddling the ends of the plates, pivoted to one of the plates on pin 55 and provided with a finger piece 56 by means of which the clamp is readily moved 30 to and from its clamping position. It is understood from this construction that releasing the clamp permits the cable to be threaded between the plates and the pulley so 35 that when the clamp is in operative position there is no possibility of the cable escaping from the pulley.

In the modified form of the elevator 40 mounting shown in Fig. 5, a peripheral cam shaped hub 57 is secured to the pivotally mounted end of the elevator and a flexible extension 58 from the spring 44 underlaps and is trained about the periphery of the cam and secured thereto at 59. The cam is laid 45 out so as to compensate in lever arm length for the varying resistance of the spring as the elevators are shifted incidental to the raising or lowering of the suspended heater. With a properly designed cam and spring the elevators will automatically take up the slack 50 from any position at which the heaters may be set, and there will be no variations in resistance to the shifting of the heaters irrespec- 55 tive as to their position in the space beneath the chandelier.

Referring to the modified form of the central support of the elevators shown in Figs. 7 and 8, the central support 14 of the preceding figures is replaced by a depending post 60, the upper end of which is threaded into the support 10. Threaded on to the upper portion of the post 60 is a collar 61 between the top of which and a nut 62 is contained the top of the dome 18. The lower end of the

collar 61 is provided with an outstanding 65 flange 63, the periphery of which is outlined by steps 64, one for each of the elevators pivotally connected to the post 60 therebelow. Threaded into each of the step faces 64 is a stop 65 adapted to constitute an adjustable 70 abutment for receiving the elevators as they are swung into their upstanding positions as shown in dotted lines in Fig. 7.

To the bottom of the post 60 is screwed an elevating supporting collar 66 provided with 75 an outstanding flange 67. The periphery of the flange is stepped to correspond to the steps 64 in number on the upper collar. Each of the steps 68 is provided with a rectangular recess 69 for receiving the inner end 70 of the 80 elevators 23, it being understood of course that there is one recess for each elevator. Instead of having the elevators extend radially from the center of the support as indicated in the showing in Fig. 2, the elevators in the 85 modified form have their inner ends slightly overlapping each other considered circumferentially in one direction so as to economize in space and reduce the all-over diameter of the dome as a whole and at the same time 90 provide the maximum possible length to the elevators. For this purpose the recesses 69 extend as far as is practically possible into the flange 67 and are disposed substantially 95 parallel to a tangent to the outer periphery of the collar portion 66. The inner ends of the elevators are pivotally mounted on pins 71 driven into the flanges 67 to extend across the recesses 69. The stepped construction of the periphery of the flange 67 provides access along the exposed faces 72 to permit the insertion and withdrawing at will of the pivoting pin. Differently defined, the elevators 100 extend in direction each substantially tangent to a centrally positioned circle such as the outer periphery of the collar 66.

In operation, it is understood that the chandelier functions as is at present known in similar devices now on the market. Normally, the heaters are elevated up close to the 110 underside of the cover plate when not in use and the operator simply reaches up and draws the heaters into position one after the other as they are needed, leaving elevated any heaters which might not be required for any 115 particular treatment. With certain, or all of the heaters in operative position, the operator turns on the current to either the entire set or preferably to those heaters which are in use and which control is attained by 120 switches forming no part of the present disclosure.

As each heater is lowered into operative 125 position it will draw on its associated cable and the cable will react through the pulley on its associated elevator to depress the same from the dotted line or towards the full line position shown in Fig. 1. Even with the

form of elevators shown in Figs. 1-4, there will be a tendency for the heaters to remain wherever they may happen to be set. In the cam form of spring actuated elevating means shown in Fig. 5, the lifting tendency of the spring acts simply to counterbalance the weight suspended from the pulley and this weight leverage will be constant and substantially independent of the angle of the elevator relative to its limiting positions.

Should any one heater, its cable or associated elevator, become damaged, inoperative or worn or for any other reason requiring replacement, the dome may be readily removed or the cover plate lowered and the elevator disconnected as previously suggested. The parts removed can be dropped out through the passageways in the bottom of the device and the remaining part restored for operative use. The cable can be disconnected from its elevator simply by releasing the clamp and the damaged part returned to the factory for repair, after which the repaired part or a substitute part may be replaced as is obvious.

It is possible when using the form of elevator mounting shown in Figs. 7 and 8 to increase the length of the elevators over the length shown in the form of mounting disclosed in Fig. 1 without enlarging the overall dimension of the device. The rigid collar for pivotally supporting the elevators can be made sufficiently massive to withstand strain incidental to use and at the same time the staggering arrangement of the elevators in their lapped positions provides the necessary space to accommodate the longer elevators.

By means of a device such as is herein disclosed, it is possible for the unskilled operator to remove a damaged part without materially affecting the usefulness of the device as a whole and where substitute parts are carried in stock any damaged part may be quickly replaced and the entire device restored for operation.

Having thus described my invention, I claim:

1. A device of the class described, including an elevator comprising a pair of parallel, spaced apart side plates, means spaced from one end for securing the sides in their normal spaced apart positions, said plates provided adjacent said end with integral and transversely aligned pivot studs, a pulley provided with a central aperture adapted to receive said studs and a clamp at said end for securing the sides with the studs in the pulley and said pulley mounted for rotary movement on said aligned studs.

2. In a chandelier for supporting and supplying electric energy to an electric instrument, the combination of a support including a fixed pivot pin, elevating means for raising the instrument, said means provided with an upwardly facing slot containing said pin

and coacting therewith to provide a readily detachable pivotable connection between the elevating means and the support and an upwardly extending spring tending to elevate the free end of said means and also acting to maintain the pivotal connection in place, and a cable trained over the free end of said means, with an end of the cable falling from said means and adapted to be connected to the electric instrument.

3. In a device of the class described, the combination of a horizontally disposed guide mounting plate provided with a relatively large passageway and a slot communicating with said passageway, a cable guiding ring located in the slot and provided with means for securing it to the plate, said ring adapted to be removed through the passageway when loosened from the plate, and a cable supported above said ring and having a portion falling below the plate and guided through the ring.

4. In a device of the class described, the combination of a horizontally disposed guide mounting plate provided with a relatively large passageway and a slot communicating with said passageway, a cable guiding ring located in the slot and provided with means for securing it to the plate, said ring adapted to be removed through the passageway when loosened from the plate, and a cable supported above said ring and having a portion falling below the plate and guided through the ring, and an electric instrument secured to the depending end of the cable and adapted to be passed therewith through said passageway in mounting and demounting the cable with the instrument attached thereto from the device.

5. In a device of the class described, the combination of a casing including a horizontally disposed guide mounting plate provided with a relatively large passageway and two slots connecting therewith, a pair of spaced apart cable guides secured to the plate, one in each slot and adapted to be removed through the passageway, cable elevating means in the casing, one above each guide and cables depending from each of said means and each threaded through its associated guide, and said guides acting to maintain the cables separated from each other and thus tend to minimize intertangling as they fall from the device.

6. In a device of the class described, the combination of a mechanism containing casing including a central cone, cable elevators extending radially from the cone, an annular hollow box outlining the lower end of the cone, the outer face of said box provided with a plurality of electric sockets, a main electric lead extending from within the cone through the box, branch conductors extending in the box circumferentially from the main lead to the several sockets, and electric cables lead-

ing from the sockets over the elevators, one cable to each elevator depending therefrom and adapted to be connected to an electric instrument.

5. 7. In a device of the class described, the combination of a lever constituting an elevator and pivotally mounted at one end, a

peripheral cam secured to the lever at its pivoted end, and a spring acting on the cam to elevate the lever.

Signed at New York, in the county of New York and State of New York, this 12th day of March, A. D. 1927.

EDMUND M. ERB.
